AUXILIARY PRESSER FOR FLAT KNITTING MACHINES

Woldemar Heinitz, Chemnitz, Germany, assignor to Schubert & Salzer Maschinenfabrik Aktiengesellschaft, Chemnitz, Germany

Application December 17, 1935, Serial No. 54,905
In Germany December 17, 1934

2 Claims. (CL 66—98)

The present invention relates to flat knitting machines and is more particularly concerned with auxiliary presses for such knitting machines.

5 Auxiliary presses for actuating a portion or a number of the frame needles for instance in the manufacture of the heel portions of stockings are known already. Moreover, it has already been proposed to subdivide neither the needle 10 bar nor the presser, but to provide, in the range of the heel portions, a special presser which is brought into operative position during the manufacture of the heel portions only.

According to the present invention the auxiliary presser is used also for the formation of 15 beginning or starting rows of loops. The auxiliary presser according to the invention consists of a presser comb carrying two kinds of press instruments which alternate with each other. The one kind of press instruments has a longer 20 head than the other kind of instruments.

The presser comb may be lifted into two different operative positions. In its uppermost position, the press points of both kinds of press instruments, i. e. of the press instruments having a long head as well as of the press instruments having a short head, lie in the level of the heads of the frame needles, so that all frame needles are pressed. In an intermediate position, the 25 press instruments having a long head only are lifted so far, that their press point is situated in the level of the heads of the frame needles. Consequently the frame needles coordinated to the press instruments having a long head only are 30 pressed, while the press instruments provided with a short head and situated below the heads of the frame needles are prevented from pressing their frame needles. During the manufacture of the leg portion of a stocking, the auxiliary 35 presser is withdrawn and occupies a position below the presser edge proper of the knitting machine. During the manufacture of the heel portions, the auxiliary presser is brought in front of the presser edge, so that all frame needles used 40 for forming the loops of the heel portions are pressed. During the manufacture of the starting or beginning rows of loops of the sole portions, the auxiliary presser is brought in front of the presser edge, so that only the one kind of 45 press instruments, i. e. those provided with a long head, operate. During the manufacture of the sole portions, the auxiliary presser is again withdrawn below the presser edge proper.

In the accompanying drawings one embodiment 50 of the invention is shown by way of example.

In these drawings:

Fig. 1 shows a part sectional side elevation of the auxiliary presser according to the invention in the position of rest,

Fig. 2 is a broken away part sectional side elevation of the auxiliary presser in an operative position in which all the frame needles, forming the heel portions, are pressed, i. e. plain loops are formed,

Fig. 3 is a part sectional side elevation of the auxiliary presser, showing the individual parts in an operative position in which only the press instruments having a long head operate,

Fig. 4 shows in front elevation a portion of the auxiliary presser,

Fig. 5 is a detail view on an enlarged scale of an auxiliary press instrument with a long head and a press instrument with a shorter head,

Figs. 6 and 7 show detail views on an enlarged scale of press instruments and frame needles in two different operative positions, and

Figs. 8—10 show diagrams of loops produced during the manufacture of the beginning or starting courses.

In the jack sinker bearing 1 the usual jack 25 sinkers 2 are arranged and the frame needles 4 may cooperate with the usual presser edge 3.

Upon a shaft 5 rotatably journalled in the frame of the machine, not shown in the drawings, levers 6 are fixed which carry the presser frame 7. The presser frame 7 carries the presser combs 8 which in the range of the heel portions are provided with press instruments 25 and 26 having a long head 9 and a short head 10 respectively, as best shown in Figs. 4 and 5.

Connected to the shaft 5 is a lever 11 the free end of which carries a displaceable roller 12. A tension spring 22 is connected with its ends to the lever 11 and to a fixed point of the frame of the machine. The position of the roller 12 may be adjusted by means of a fork 14 mounted upon a rod 13, shiftably arranged in the frame of the machine.

Upon a cam shaft 15, also mounted in the frame of the machine, a circular disc 16 and two cams 17, 18 are fixed into the path of which the roller 12 may be shifted.

By means of a spring 19 the presser frame 7 is constantly drawn in a direction towards the jack sinker bearing 1. The presser frame 7 carries projections 20 having an inclined surface 23. Fixed to the jack sinker bearing 1 are projections 21 also having an inclined surface 24. The projections 20 and 21 are arranged in such a manner, that, when the presser frame 55

7 occupies its position of rest, the inclined surfaces 23 and 24 of these projections are in contact with each other as shown in Fig. 1.

During the manufacture of ordinary or plain 5 rows of loops, the press instruments 25, 26 occupy the position shown in Fig. 1. The roller 12 carried by the lever 11, runs on the circular disc 16. The frame needles 4 are pressed directly at the presser edge 3, as in the case of 10 any normal knitting machine for the manufacture of the leg portions of stockings.

During the manufacture of the heel portions at which time the needles forming the instep portion of the stocking are, in a well known manner, placed in suspense, the auxiliary presser combs, affecting the needles forming the loops of the heel portions, are brought into the position shown in Figs. 2 and 6. For this purpose the roller 12 is shifted into the path of the cam 20 17. In this position of the individual parts, the head 9 of the press instruments 25 as well as the head 10 of the press instruments 26 lie in front of the presser edge 3, so that all the needles used for forming the loops of the heel portions are 25 pressed by the heads 9 and 10 of the press instruments 25 and 26 respectively. Plain loops are formed in this manner. In the instep portion, pressing of the needles is not effected, as the auxiliary pressers are provided in the range of 30 the heel portions only and the bar, carrying the frame needles, or the heads of the frame needles are, during the formation of the heel portions, prevented from swinging into the range of the presser edge 3, but allowed to swing into the 35 range of the heads 9 and 10 of the auxiliary press instruments 25 and 26 only.

After finishing the heel portions, the roller 12 is, for the purpose of manufacturing the starting or beginning rows of loops of the enlarged 40 sole portions, shifted into the path of the cam 18. Hereby the auxiliary presser combs are brought into the position shown in Figs. 3 and 7 in which those frame needles 4 only are pressed which lie opposite the press instruments 25 provided with a long head 9. The frame needles 4, lying opposite the press instruments 26 having a short head 10, are, however, not pressed.

As soon as the desired number of beginning or starting rows of loops, pressed in the manner 50 described, has been formed, the auxiliary presser combs 8 carrying the press instruments 25, 26 are returned into the position shown in Fig. 1 in which the heads 9 and 10 of the press instruments 25, 26 lie below the presser edge 3 proper. 55 To obtain this position of the parts, the roller 12 is shifted again into the path of the circular disc 16. On further knitting, the frame needles 4 are pressed again by the presser edge 3 proper. The displacement of the roller 12 into the path

of the circular disc 16 and the cams 17 and 18 respectively may also be effected in any other suitable manner.

Figures 8-10 diagrammatically show the manufacture of the loops of a starting or beginning 5 row.

According to Fig. 8 it has been assumed, that the press instruments 25, 26 are shifted into the operative position shown in Figs. 3 and 7, so that only the instruments 25 provided with a long 10 head 9 press their corresponding frame needles a, c, e. The loops hanging on these frame needles may, therefore, be knocked off. The frame needles b, d, f, situated opposite the press instruments 26 having a short head 10 are, however, not pressed, so that, as shown in Fig. 9, the loops remain on these needles with the result, that, as illustrated in Fig. 10, tuck loops are formed on these frame needles b, d, f.

What I claim is:

1. An auxiliary presser for flat knitting machines, comprising a jack sinker bearing, a presser edge provided at said jack sinker bearing, press instruments having a short head and press instruments having a long head alternating with 25 each other, a frame carrying said alternately arranged press instruments, levers pivotally connected to the lower end of said frame, a rotatable shaft mounted in the frame of the machine and carrying said levers, a lever arm carrying a roller 30 at its end and fixed upon said shaft, a circular disc and two cams of different height adapted to cooperate with said roller to rotate said shaft and bring said frame in its different positions of height, and projections, having cooperating 35 inclined surfaces, provided at said frame and at said jack sinker bearing of the knitting machine respectively, the arrangement being such, that the press instruments may occupy an inoperative position in which their heads lie below the presser 40 edge of the knitting machine and two operative positions in which the press points of the instruments having a long head only and the press points of all the instruments respectively are situated in front of the corresponding frame 45 needles, resulting in pressing alternating frame needles only and all of the frame needless respectively.

2. An auxiliary presser for flat knitting machines comprising a jack sinker bearing, a presser 50 edge provided at said jack sinker bearing, press instruments with heads of different lengths arranged in an alternate order of succession with regard to the length of the heads, a frame carrying said press instruments, means for lifting said frame in different positions of height with regard to said presser edge, and means for swinging said frame simultaneously with its lifting.

WOLDEMAR HEINITZ.
